UNITED STATES PATENT OFFICE.

LOUIS E. GAISSER, OF LOUISVILLE, KENTUCKY.

WRENCH.

1,160,160.

Specification of Letters Patent.

Patented Nov. 16, 1915.

Application filed April 29, 1915. Serial No. 24,775.

To all whom it may concern:

Be it known that I, LOUIS E. GAISSER, a citizen of the United States, residing at Louisville, in the county of Jefferson and

5 State of Kentucky, have invented a new and useful Wrench, of which the following is a specification.

This invention relates to improvements in wrenches, one of its objects being to provide 10 a wrench which may be instantly adjusted to objects of different sizes and promptly disengaged therefrom without the operation of rotating an adjusting screw or the like such as is commonly necessary.

15 Another object is to provide a wrench which is formed of but few parts, can be made at slight cost, is durable, and will not readily get out of order.

A further object is to provide a wrench 20 the parts of which are so assembled as to relieve the fastening means and pivots of lateral strains, which would tend to break and unduly wear the parts.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

In the accompanying drawings the preferred forms of the invention have been shown.

In said drawings:—Figure 1 is a plan view of a wrench embodying the present improvements. Fig. 2 is a side elevation thereof. Fig. 3 is a plan view with the cover plate removed, a portion of the slide being shown in section. Fig. 4 is a section on the line A—B of Fig. 1. Fig. 5 is a perspective view of the removable jaw and its slide. Fig. 6 is a perspective view of the fixed jaw and the head of the wrench, the cover plate being removed. Fig. 7 is a plan view of the head of the wrench constructed for use as a pipe wrench. Fig. 8 is a view partly in longitudinal section and partly in elevation of a slightly modified form of wrench. Fig. 9 is a section on line C—D Fig. 8. Fig. 10 is a plan view of a modified form of lever. Fig. 11 is a transverse section through a modified 50 form of slide. Fig. 12 is a transverse section through another form of slide.

Referring to the figures by characters of reference 1 designates the head of the wrench, the same being provided with a shallow angular channel 2 extending from one side to the other thereof. From the front of this head projects the fixed jaw 3 of the wrench and, as shown, the top of the jaw may be formed at the outer side thereof with an angular recess 4. Upstanding from the rear portion of the head adjacent each side thereof are bosses 5, the top faces of the bosses being in the same plane with the top of the jaw 3 and each boss as well as the jaw being provided with a threaded 60 stud 6 extending upwardly therefrom. One of the bosses 5 has a rounded finger piece 7 extending obliquely therefrom. Formed in the head 1 and between the bosses is an opening 8.

Slidably mounted in the channel 2 is a block 9 from which extends a movable jaw 10 of the wrench, this movable jaw being located at one end of the block and there being an opening 11 extending through the 65 block from the front to the rear thereof. As shown particularly in Fig. 3 the end walls of the opening 11 are preferably ogee shaped, as at 12 although it is to be understood that they can be of any other contour 70 desired. The jaw 10 is extended upwardly and downwardly beyond the block 9 from which it extends and is designed to lap the front face of the head 1 and to likewise lap the front edge of the cover plate 13 which 75 rests on the jaw 3 and the bosses 5 and has openings 14 for the reception of the studs 6. An opening 15 is formed in the cover plate 13 between the bosses 5 and it is to be understood that the rear corner portions of the 80 cover plate 13 are cut away to form seats for engaging the upper ends of the bosses 5, as shown in Fig. 4 wherein the seats have been illustrated at 16. Furthermore the cover plate is provided, upon that portion 85 thereof engaging the fixed jaw 3, with an angular extension 17 adapted to rest within the recess 4.

Extending into the openings 8 and 15 are trunnions 18 extending upwardly and downwardly from a combined handle and lever 19 one end of which is extended into the opening 11 in block 9 and has a head 20 formed with rounded sides adapted to engage the walls 12 of the opening 11.

In assembling the parts the head 20 of lever 19 is inserted into opening 11 and

2

block 9 is placed on the head 1 so as to work transversely of the head within the groove 2. The cover plate 13 is then positioned on the head, the projection 17 extending into the recess 4 while the bosses 5 project into engagement with the cut away portions or seats 16. Nuts 21 are then placed on the studs 6 and tightened so as to bind the plate 13 tightly upon the jaw 3 and the bosses 5 or, if preferred, instead of providing nuts, the studs 6 can be upset thus to constitute rivets for holding the parts together. With the parts thus assembled it will be apparent that by swinging handle 19 in one direction relative to the head 1, the block 9 will be slid so as to move jaw 10 away from the jaw 3 whereupon an object to be gripped can be placed between the jaws. By then swinging handle 19 in the opposite direction, jaws 10 and 3 will be adjusted toward each other and bind upon the inserted object, the degree of pressure upon said object increasing in proportion to the pressure exerted upon the handle or lever 19. By means of the finger piece 7, the head 1 and handle or lever 19 can be readily shifted relative to each other for the purpose of applying the jaws to or disengaging them from the object therebetween. By providing the seats 16 in the rear corners of the cover plate 13 and by providing the projection 17 for extending into the recess 4 it will be apparent that the cover plate, when in position, is held against lateral shifting relative to the head 1 and, consequently, the studs 6 are relieved of transverse strain and the same is likewise true of the trunnions 18.

It is to be understood that instead of constructing the wrench with straight jaws such as used for engaging nuts and bolts, the said jaws can be formed with recesses 21, as shown in Fig. 7, each recess receiving a toothed jaw plate 22 dove-tailed into the jaw as shown and adapted to be secured by means of a binding screw 23. Thus the wrench would be adapted for use as a pipe wrench.

In Fig. 8 another modified form of wrench has been illustrated. This wrench includes a slide 24 which may be similar to the block 9 and which carries a jaw similar to the jaw 10 or of any other desired construction. The recess 25 in the block 24 receives one end of a lever 26 having its trunnions 27 surrounded by ball races 28, the balls 29 in these races being arranged to bear upon opposed walls of the wrench, as shown in Fig. 8. Thus friction is materially reduced. As a means for preventing the block or slide 24 from shifting readily out of proper position during the adjustment of the wrench, a groove 30 may be formed in the plate 31 which corresponds with the plate 13 and in this groove may be seated a spring 32 bearing frictionally against the

slide or block 24 so as thus to resist the movement of said block. Consequently the block will remain in any position to which it may be pushed by the lever 26 and no difficulty will be experienced in adjusting the wrench.

Instead of shaping the lever as heretofore described, the same may be formed with oppositely extending rounded wings 33 at the block engaging end thereof, thus to present rounded friction surfaces. Furthermore, the lever may be formed with bearing trunnions 34, the diameter of which is equal to the width of the lever. This construction has been shown in Fig. 10. Instead of forming the blocks 9 and 24 with slots or recesses such as shown for example in Fig. 3, the side walls 35 of the recess 36 may converge toward the jaw 37 carried by the block or, if desired, and as shown in Fig. 12, the side walls of the recess 38 in the block may be rounded, as at 39, thus to provide a smooth bearing for the rounded portions 33 of the shifting lever.

Obviously various other modifications may be made in the construction of the wrench without departing from the spirit of the present invention.

What is claimed is:—

1. A wrench including a transversely grooved head, upstanding spaced bosses thereon, a fixed jaw extending forwardly from the head and upstanding therefrom, a block slidably mounted within the groove of the head, a jaw movable with the block, the block having an opening therein, a cover plate bearing upon the fixed jaw and bosses and projecting between the bosses, fastening means extending from the bosses and the fixed jaw and into the cover plate, said bosses coöperating with the cover plate to relieve the fastening devices of transverse strain, a combined handle and lever projecting into the opening in the block, and trunnions extending from the lever into the head and cover plate.

2. In a wrench the combination with a head and a transverse groove, a fixed jaw upstanding from the front of the head, bosses upstanding from the rear corner of the head, and a finger piece extending from one of the bosses, of cover plate bearing upon the jaw and bosses and having cut away corners for the reception of the bosses, said bosses and cover plate coöperating to hold the plate against lateral displacement relative to the head, a projection on the cover plate engaging the fixed jaw, studs on the fixed jaw and bosses for engaging the cover plate to hold it upon the said jaw and bosses, a block slidably mounted in the grooved head and retained by the cover plate, a jaw movable with the block, said block having an opening, a lever projecting into the opening in the block and trunnions upon

the lever engaging the head and cover plate at points between the bosses.

3. A wrench including a transversely grooved head, upstanding spaced bosses thereon, a fixed jaw extending forwardly from the head and upstanding therefrom, a block slidably mounted within the groove and the head, a jaw movable with the block, the block having an opening therein, a cover plate bearing upon the fixed jaw and bosses and projecting between the bosses, fastening means extending from the bosses and the fixed jaw and into the cover plate, said bosses coöperating with the cover plate to relieve the fastening devices of transverse strain, a combined handle and lever projecting into the opening in the block, trunnions extending from the lever into the head and cover plate, and a spring interposed between the cover plate and bearing against the block.

4. A wrench including a head, a fixed jaw extending forwardly therefrom, a block

slidably mounted within and adapted to move transversely of the head, a jaw movable with the block, a bow spring seated in the head and frictionally engaging the block, a combined handle and lever pivotally mounted in the head and extending therebeyond, means within said head for transmitting motion from said combined handle and lever to the block to slide said block transversely of the head during the pivotal movement of the combined handle and lever, and a finger piece fixed on the head and extending rearwardly therefrom in reach of a hand grasping the combined handle and lever.

In testimony that I claim the foregoing as my own, I have hereto affixed my signature in the presence of two witnesses.

LOUIS E. GAISSER.
